A. KIRSHNER

CHRISTMAS TREE SUPPORT

Filed April 13, 1927

INVENTOR:

Abraham Kirshner.

BY

Middechney & Van Buren

ATTORNEYS.

UNITED STATES PATENT OFFICE.

ABRAHAM KIRSHNER, OF PHILADELPHIA, PENNSYLVANIA.

CHRISTMAS-TREE SUPPORT.

Application filed April 13, 1927. Serial No. 183,266.

This invention, generally stated, relates to an article of hardware and has more especial relation to a knock-down type of article which may be employed to support a Christmas tree.

The leading object of the present invention may be said to reside in the provision of an article of the character stated formed of three pieces of metal which may be sold 10 in compact form for a very small sum and which may be readily extended by the purchaser to form a tripod effect for securing in position a Christmas tree.

A further object of the present invention is to provide a metallic frame of the character stated having a base part the respective portions of which are pivotally secured together and the arms of which are bent at an acute angle with respect to the base parts, 20 both the base parts and arms being adapted to be nailed to the floor or other support and the upper parts of the arms being adapted to be nailed to a Christmas tree.

Other and further objects of the present 25 invention reside in the provision of general details of construction, arrangement, combination, and connection of parts for attaining the results sought by the leading object.

The invention consists of the novel construction hereinafter described and finally claimed.

The nature, characteristic features and scope of the invention will be more fully understood from the following description 35 taken in connection with the accompanying drawings forming part hereof, and in which:

Fig. 1, is a top or plan view of a Christmas tree support embodying the invention.

Fig. 2, is a view in elevation of a Christmas tree support embodying the invention including the trunk of a Christmas tree in position.

Fig. 3, is a fragmentary view in plan of 45 the pivotally arranged base parts.

Fig. 4, is a view of a combined base and arm part in distended position.

Fig. 5, is an edge view of Fig. 4.

Fig. 6, is a fragmentary view hereinafter referred to.

Figs. 7 and 8 are respectively cross sectional views taken upon the lines 7—7 and 8—8 of Fig. 4.

For the purpose of illustrating my invention 55 I have shown in the accompanying drawings one form thereof which is at pres-

ent preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the Christmas tree support is made of metal throughout and is arranged to provide a tripod effect and generally stated comprises

three base members 1 having pivotal relation with each other as at 2, see Fig. 3. The base members 1 are horizontally extended and in cross section are reinforced longitudinally as at 3 by stamping a rib centrally of each member 1. The free ends of each member 1 are weakened along the lines 4 so

that the ends may be turned upwardly at an acute angle to the base members to provide arms 5, the upper extremities of which terminate in vertically disposed extensions 6.

The arms 5 in cross section, as clearly shown in Fig. 7, are provided with longitudinally extended ribs 7 for reinforcing said arms. Adjacent the weakened lines 4 the said base

members 1 and the arms 5 are apertured as at 8—9 so that nails 10 may be driven through the apertures to hold the base part of the device to the floor 11. With the arms

folded at an acute angle to the base members as clearly shown in Fig. 2, these apertures 8—9 are in alignment so that a nail may be driven through both of said members into the floor, as is best seen in Fig. 2. In

practice the Christmas tree is positioned upon the central portion of the base members 1 and nails 12 driven through the apertures 13 of the base members up into the tree 14. The extensions 6 of the arms 5 are positioned around the tree 14 and nails 15

driven through said apertures to securely 100 clamp and hold the Christmas tree in upright position. In practice the Christmas tree support is made entirely of metal and each combined base part and arm are

stamped from a single piece of metal with 105 the ribs and nail receiving apertures as previously described. Since all the members are pivoted together as at 2 it is readily apparent that the device as a whole may be

sold with the three arms and base parts longitudinally positioned in folded form and that after purchase the customer may bend

the arms 5 upwardly and inwardly about the weakened parts 4 to the position shown in Fig. 2.

The showing in Fig. 6 is a detail of one of the base members 1 detached with respect to the other base members, or in other words, prior to attaching the base members together. The apertures 16 are calculated to receive the rivets 2 as shown in Fig. 3.

10 It will be seen from Figs. 3 and 4 that the ends of two of the base members are bevelled as at 17, so that when they are turned in to operative position as seen in Fig. 3, said bevelled edges abut and when the nails 12 15 are driven through the aligning holes 13, they not only secure the base members to the bottom of the tree but they lock the three members 1 in the position seen in Fig. 3.

It will be evident that Fig. 6 shows the 20 end of one of the base members, while the end of the other two base members appears as seen at the right of Fig. 4, and in Fig. 3.

Having thus described my invention, what I claim as new and desire to secure by Letters Patent, is:

1. In a device of the character stated, a tripod construction consisting of base members pivotally connected together at their innermost ends and having their outer ends 30 bent upwardly and inwardly at an acute angle to form arms, the extremity of each of which is bent upwardly to form vertical extensions, the end of one of said base members being provided with four holes and 35 the coacting ends of the other two members

being bevelled and provided with two holes, the outer holes in said members aligning, when said members are in operative position.

2. In a device of the character stated, a 40 tripod construction consisting of base members pivotally connected together at their innermost ends and having their outer ends bent upwardly at an acute angle to form arms, the extremity of each of which is bent 45 upwardly to form vertical extensions, both said members and said arms being provided with longitudinal reinforcing ribs, an intermediate weakened portion and holes on each side of said weakened portion in proximity 50 thereto, the end of one of said base members being provided with four holes and the coacting ends of the other two members being bevelled and provided with two holes, the outer holes in said members aligning, 55 when said members are in operative position.

3. In a device of the character stated, a plurality of base members pivotally secured together, two of said members being provided with bevelled abutting edges having holes, and longitudinal stiffening ribs for the end portions of said members, the latter being provided with transverse weakened 60 portions intermediate said ribs and holes on each side of said weakened portions in 65 proximity thereto.

In testimony whereof, I have hereunto signed my name.

ABRAHAM KIRSHNER.
